(57) CLAIM

The ornamental design for a bouquet as shown and described.

DESCRIPTION

FIG. 1 is a perspective view of a bouquet showing our new design.

FIG. 2 is a bottom perspective view thereof.

FIG. 3 is a front view thereof.

FIG. 4 is a back view thereof.

FIG. 5 is a right-side view thereof.

FIG. 6 is a left-side view thereof.

FIG. 7 is a top view thereof; and,

FIG. 8 is a bottom view thereof.

The broken lines shown in the Figures show portions of the bouquet that form no part of the claimed design.

The shade lines in the Figures show contour and do not claim surface ornamentation or treatment.

1 Claim, 8 Drawing Sheets
